(57) **CLAIM**

The ornamental design for a cosmetic container with sleeve, as shown and described.

DESCRIPTION

FIG. 1 is a front perspective view of a cosmetic container portion in an open configuration of a cosmetic container with sleeve showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view thereof in a closed configuration; and,

FIG. 9 is an exploded perspective view of a cosmetic container with sleeve showing my new design.
